[57] CLAIM

The ornamental design for a raised deck sport roof for a van, as shown and described.

DESCRIPTION

FIG. 1 is a front elevation view of a raised deck sport roof for a van embodying my new design;

FIG. 2 is a side elevation view thereof;

FIG. 3 is a rear elevation view thereof;

FIG. 4 is a top plan view thereof;

FIG. 5 is a perspective view thereof; and

FIG. 6 is a perspective view of a raised deck sport roof for a van showing a second embodiment of my new design, the sole difference being in the addition of a railing unit.

FIG. 1

FIG. 2

FIG. 3

FIG. 4

FIG. 5

FIG. 6
